UNITED STATES PATENT OFFICE.

SETH WARD, OF PRINCETON, INDIANA.

REIN-GUIDE.

SPECIFICATION forming part of Letters Patent No. 361,472, dated April 19, 1887.

Application filed January 24, 1887. Serial No. 225,339. (No model.)

To all whom it may concern:

Be it known that I, SETH WARD, a citizen of the United States, residing at Princeton, in the county of Gibson and State of Indiana, have invented certain new and useful Improvements in Rein-Guides, of which the following is a specification, reference being had therein to the accompanying drawings.

My invention relates to improvements in rein-guides, it being particularly designed to be placed upon the hip-straps of the harness.

This invention relates to an improvement in rein-guides, which will be fully understood from the following description and claim when taken in connection with the annexed drawings, in which—

Figure 1 represents a perspective view of my improved device, showing the driving-rein in broken lines, and Fig. 2 a side elevation of 20 the same, showing the strap to which it is attached in broken lines.

Referring to these drawings by letter, A A designate two buckle-frames, curved as shown in the drawings, which are connected together 25 by the arch B, through which the driving-rein passes, and which is formed integral with the buckle-frames. The said frames are constructed with transverse end bars, b b, and transverse rounded bars a a'.

One of the cross-bars of the buckle frames is provided with a spur or teat, C, for adjusting and holding the device upon the strap to which it may be applied, the strap being perforated for the passage of the spur; also connecting the two buckle-frames; and below the arch B is a friction-bar, D, the upper surface 35 of which may be rounded, and which not only serves to support the rein and keep it from

contacting with the hip-strap, but also strengthens the device materially, as is evident.

The device, as thus constructed, will be very inexpensive, as it may be cast complete, out of any suitable metal, by a single operation.

The device is applied to a hip or other strap by looping the same around the cross-bars of 45 the buckle-frames, as shown in dotted lines in Fig. 2 of the drawings, the strap passing across from one frame to the other under the connecting-bar D, over the cross-bars a a', and under the cross-bars b b.

Instead of placing the device upon a hip-strap, as I now prefer, it is evident that I may apply it to any part of the harness, if I should so desire, without in the least departing from 50 my invention.

I am aware that it is not new in rein-guides to employ an arch or loop having short loops and a connecting-bar, and therefore I disclaim such devices, broadly.

Having thus fully described my invention, 55 what I claim, and desire to secure by Letters Patent, is—

The within-described improved article of manufacture, consisting of the rectangular curved frames A A, each provided with a cross-bar, and one bar having a pin, C, the bar D, and the arch B, all formed of one piece of metal, the end bars, b b, being under beveled, all as shown and described.

In testimony whereof I affix my signature in 70 presence of two witnesses.

SETH WARD.
